BOTTLE CLOSURE SEALING BAND

Allan B. Colby, Lancaster Township, Lancaster County, Pa., assignor to Armstrong Cork Company, Lancaster, Pa., a corporation of Pennsylvania

Application April 29, 1936, Serial No. 76,882

3 Claims. (Cl. 215—95)

This invention relates to a sealing band for bottle closures and the like formed of a strip of ductile metal capable of being ruptured along a score line or other weakened portion, said strip being disposed at an overlapped portion thereof.

It is an object of my invention to provide a sealing band for bottle closures formed of ribbon material which may be procured in indefinite lengths at low cost and which may be shaped into a preformed seal by automatic machinery without the necessity of "long draws" or other complicated dieing or drawing operations. Another object of my invention is to provide a sealing band in which any attempted unsealing thereof will result in destruction of a portion of the band, thus indicating an attempt to adulterate the contents or remove the seal for some other illegal purpose.

The sealing band of the present invention is adapted for use with various types of bottle closures including corks, either plain or flanged, wood or composition topped, metal or molded closures and the like, and comprises essentially a strip of ductile metal of relatively light weight and readily spinnable character, such as aluminum, disposed as a substantially cylindrical band and adapted to embrace the closure to be sealed and a portion of the container to which the closure is applied, securing means disposed at an overlapped portion of the strip and preferably formed of the material of the strip, a digit engageable portion or tab to facilitate unsealing and means of disclosing any unlawful attempted unsealing thereof.

One embodiment of my invention is illustrated in the accompanying drawing in which

Figure 1 is a side elevation of a bottle having a closure sealed with the sealing band of my invention; and

Figure 2 is a sectional view on line II—II of Figure 1.

Referring first to Figure 2, the closure for the receptacle 2 comprises a cork stopper 3 having a flanged wood top 4. This is a conventional closure commonly employed. The illustrated sealing band, generally indicated by the numeral 5, comprises a cylindrical skirt 6 and an inwardly, radially extending flange 7 embracing the wood top 4 of the cork stopper 3.

It will be observed, by reference to Figure 1, that the material of the band is overlapped at 8 a distance sufficient to permit sealing of the strip. The preferred sealing means comprises a pair of integrally formed rivets 9 and 10 which are preferably formed at the factory, but may be

partially formed there and the final sealing of the band effected by the bottler. The rivets 9 and 10 comprise eyelets 11 and 12 formed in the inner ply 13 of the overlapped portion 8 of the band. Outer ply 14 is perforated and the eyelets 11 and 12 pass therethrough and are flanged radially therearound as indicated at 15 to provide a firm connection for the plies 13 and 14, securing the strip as a substantially cylindrical band. If the bottler be supplied with flat strips, the eyelets and corresponding perforations will be formed therein and formation of the sealing rivets will be effected prior to assembly of the band with the closure to be sealed. Except for the bulky character of completely preformed bands, it is desirable to completely fabricate the bands at the manufactory since the assembly operation may be conveniently combined with the forming operations.

In assembly of the band with the closure and receptacle to be sealed, the skirt portion 6 is slipped over the cylindrical side of the wood top stopper 4 and the bottle 2 and the lower edge 16 of the band is spun under a projection 17 provided in the bottle finish. In order to permit of a spinning operation, the material of the band should be reasonably ductile, and if aluminum be employed, it should be from approximately .005 to .010 of an inch in thickness.

In order to provide a convenient means for unsealing the band and at the same time to provide an indication to the purchaser that the seal has been tampered with, a tear tab 18 is provided which is cut from the metal of the band. In the illustrated embodiment, the tab is of generally rectangular shape and a pair of score lines 19 and 20 extend from the unexposed cut edge of the tab 18 in lines tangent to the rivets 9 and 10, and thence to the exposed edge of the outer ply 14 as shown in Figure 1. This provides a digit engageable portion, which, upon application of straining stress in a direction toward the rivets 9 and 10 will result in severance of the material of the strip along the lines 19 and 20, enlarging the digit engageable portion and directing the application of stress directly against the flanges 15 which are urged to their original, axially extending plane or straightened out and unsealing of the band effected, and that portion of the strip defined by the score lines 19 and 20 and 45 embracing the rivets 9 and 10 is removed. If the material from which the band is formed is of relatively light weight, the material of the outer ply will probably be removed upon the application of straining stress rather than effecting 50 55

opening up of the rivet flanges 15. In any event, the seal is broken by the application of digital stress exerted through the tear tab 18. The rivets 9 and 10, or other securing means which are employed in lieu thereof, should preferably hold the overlapped portions 13 and 14 sufficiently securely that the application of straining stress by the tab 18 will result in severance of the material of the band along the lines 19 and 20 to the rivets 9 and 10, or other sealing means, before opening up or breakage of the seal occurs and thus an indication will be given to the consumer that tampering with the contents has been attempted. The sealing means should also be capable of being broken by the application of relatively slight stress such as that which may be induced through a tear tab with the fingers.

The seal may be formed as an integral hollow rivet with its flange lying interiorly of the band 20 and thus additionally insure against unauthorized unsealing of the band for, when the band is in sealing position, the flange is inaccessible. If such a structure be employed, a reenforcing rib should be provided encircling the securing rivet 25 or rivets to limit the tear and to localize the application of stress to the rivet.

A structure in which the rivet is formed interiorly of the band is described and claimed in my copending application filed currently here- 30 with.

My sealing band provides an easily fabricatable structure which requires no involved drawing equipment and may be formed from a ribbon of sheet metal with simple forming operations; 35 provides a seal which is tamperproof and easily applied; and provides a structure which may be completely prefabricated prior to assembly with the closure and receptacle.

While I have described certain specific preferred embodiments of my invention, it will be understood that the invention is not limited to the form shown and described but may be otherwise embodied and practiced within the 40 scope of the following claims.

I claim:

1. A sealing band for bottle closures comprising a strip of sheet material disposed as a substantially cylindrical band with an overlapped portion, and a hollow rivet securing the overlapped portion, said rivet being flanged on the outer surface of the band, a portion of the strip constituting a digit engageable portion for applying straining stress to the rivet to break the seal formed thereby, there being a scored line extending from the digital portion to the rivet and adapted to be severed upon the application of the straining stress in an amount insufficient to break the seal. 15

2. A sealing band for bottle closures comprising a strip of sheet material disposed as a substantially cylindrical band with an overlapped portion, and a pair of integrally formed rivets securing the strip at the overlapped portion, a digit engageable portion for applying straining 20 stress in the vicinity of the rivets, there being a weakened portion extending from the digit engageable portion to the vicinity of the rivets and thence to an exposed transverse edge of the strip and severable upon the application of straining 25 stress by the digit engageable portion.

3. A sealing band for bottle closures comprising a strip of sheet material disposed as a substantially cylindrical band with the ends thereof in circumferential overlapping relationship, there being an aperture in one overlapping end of said strip, and sealing means disposed through said aperture and securing the ends of said strip together, a portion of the strip constituting a digit engageable portion for applying straining stress to the said sealing means to break the seal formed thereby, there being a weakened portion extending from the digital portion to the zone of said sealing means adapted to be severed upon the application of straining stress in any attempted 4 unsealing of the band. 30
